UNITED STATES PATENT OFFICE.

JOHN F. KAMPF, OF TOLEDO, OHIO, ASSIGNOR, BY MESNE ASSIGNMENTS, TO THE INFALLIBLE TRUSS COMPANY, OF SAME PLACE.

HERNIAL TRUSS.

SPECIFICATION forming part of Letters Patent No. 658,989, dated October 2, 1900.

Application filed January 6, 1899. Serial No. 701,338. (No model.)

To all whom it may concern:

Be it known that I, JOHN F. KAMPF, of Toledo, county of Lucas, and State of Ohio, have invented certain new and useful Improvements in Trusses: and I do hereby declare that the following is a full, clear, and exact description of the invention, which will enable others skilled in the art to which it appertains to make and use the same, reference being had to the accompanying drawings, and to the figures of reference marked thereon, which form part of this specification.

My invention relates to an abdominal truss, and has for one object to provide a truss which is easily adjustable by any one not necessarily skilled in the mechanical arts.

A further object is to provide a truss with a variable adjustment, so that a maximum or a minimum pressure can be brought to bear on a rupture, which is essential when an individual is laboring or at ease, as the case may be.

A further object is to provide this variable adjustment in a positive manner, whereby the same can be controlled by the wearer of the truss without the inconvenience of removing his outer garments or the usual necessity of retiring to a private place.

A further object is to provide a lateral adjustment of the buttons on the truss, so that pressure will be brought directly upon the rupture, no matter where its location.

A further object of my invention is to provide means for securing the same to the body independent of the support provided by the protruding hips, thus insuring against displacement of the truss.

Finally, I have provided a truss of moderate cost which can be adjusted by any one to fit any rupture and to assume a variable and positive pressure on a rupture not heretofore attained in the art.

In carrying out my invention I employ the parts and combination of parts, as hereinafter shown and described.

In the drawings, Figure 1 shows my complete truss as constructed for a double rupture, one button being adjusted to exert a maximum and the other a minimum pressure. Fig. 2 is a front elevation of my truss. Fig. 3 is a side view of my truss. Fig. 4 is a per-

spective view of the slotted plate employed to adjust the buttons laterally, also showing the method employed to attach the spring-frame thereto. Fig. 5 is a side elevation of the adjustable mechanism of the button, the button being shown in vertical cross-section. Fig. 6 is an end elevation of the same, the button being shown in longitudinal cross-section. Fig. 7 is a rear view of the button as it appears when removed from the truss, the holes which the studs enter being shown. Fig. 8 is a bottom plan view of the slotted plate to which the button is attached.

1 is a channel-plate having the spring-frames 2 and 3 secured thereto by means of clamping-plates 4 and 5. Frames 2 and 3 have suitable padded coverings 6 and 7 and are held together at the rear by means of a fastening 8. Plate 1 is formed with slots 9 and a channel 10 longitudinal thereof to receive plates 11, which are formed with guiding-studs 12, rigidly secured thereto, and a screw-stem 13, loosely journaled therein. Stem 13 has a milled nut 14 on the end thereof to permit of turning the same.

15 is a disk having a central internally-screw-threaded portion 16, into which the stem 13 is screwed.

17 are holes through which the studs 12 pass.

18 are flat-headed screws, which are designed to pass through slots 19 in the disk 15 and secure the button 20 thereto.

21 are openings in the button to allow for the passage of studs 12 and the screw-threaded portion 16 to the interior thereof, thereby not only housing the same, but forming a thoroughly-practical and compact adjusting mechanism.

22 are clips secured to plates 11 by means of screws 23 and engage the rear side of plate 1 by frictional contact when screws 23 are tightened, thereby holding plates 11, and consequently buttons 20, in any position desired laterally, the movement being limited only by the extent of the slots 9 in channel-plate 1.

In fitting the truss to the wearer the spring-wire frames 2 and 3 are made of a length to permit the padded coverings 6 and 7 to occupy a position away from the hips and to contact

only at rear at 23' and 24. In this manner the pressure on the rupture is directed positively, and there is no tendency to lateral displacement, as usual in other trusses. It is well known that the pressure on a rupture when an individual is at ease is insufficient when he is exerting himself. For this reason a positive variable adjustment the extent of which is at all times at the control of the wearer is absolutely essential. I consider this a valuable feature of my invention. When at ease the button occupies a position 20^a, Fig. 1, thereby exerting a minimum pressure on the rupture. Now where the ruptured individual is about to exert himself and desires greater pressure on the rupture he simply passes his hand in the pocket of his outer garment and turns the milled nut 14 and screw-threaded stem 13, causing the button to ride upon the guiding-studs 12 and assume a position 20^b or an intermediate position between 20^a and 20^b. In fitting the rupture when it is desired to shift the buttons laterally screws 23 are loosened, allowing plates 11 to slide freely in channel 10. When the desired position is attained, screws 23 are tightened, causing clips 22 to impinge upon the rear side of plate 1, and thereby hold plates 11 from movement. When it is desired to change the buttons from a vertical to a horizontal position, or vice versa, the screws 18 are removed, which permits the button to be withdrawn from the studs. The button is then secured in position, the studs

entering the holes arranged at right angles 35 to those which they formerly entered, their relative position having reference to an arc drawn from the axis of the screw-stem 13.

It will be seen from the foregoing description that I have provided a truss which is 40 positively and accurately adjustable as regards the position of the rupture, a variable adjustment at the control of the wearer, and a truss that is practically insured against displacement through bodily exertion. 45

What I claim is—

In a truss, a plate attached to and forming a part of the truss-frame, having a screw-stem loosely journaled therein and guiding-studs rigidly attached thereto in parallel relation, a disk adapted to ride upon said studs having a central screw-threaded portion to receive the screw-stem, the button secured to the disk and formed with a hollow interior to house the studs and the screw-threaded 55 portion of the disk, and a milled nut on the end of the screw-stem to permit of manually rotating the same and thereby imparting a variable adjustment to the button, substantially as described and for the purpose set 60 forth.

In testimony that I claim the foregoing as my own I affix my signature in the presence of two witnesses.

JOHN F. KAMPF.
